2,557,911

METHOD OF PREPARING GLYCOCYAMIDINES

**Erick I. Hoegberg, Stamford, Conn., assignor to
American Cyanamid Company, New York, N. Y.,
a corporation of Maine**

**No Drawing. Application April 19, 1950,
Serial No. 156,933**

5 Claims. (Cl. 260—309.7)

1

The present invention relates to the production of glycocyanimines, and more particularly to a method of preparing glycocyanimines of the general formula

in which R represents a member of the group consisting of alkyl and aryl radicals, and R' represents a member of the group consisting of hydrogen, alkyl and aryl radicals, such as, for example, 1-n-butylglycocyamidine, 1-n-octylglycocyamidine, 1-dodecylglycocyamidine, 1-octadecylglycocyamidine, 1-phenylglycocyamidine, 1, 3-diphenylglycocyamidine, 1-phenyl - 3 - ethylglycocyamidine, 1-phenyl-3-allylglycocyamidine, 1-phenyl-3-cyclohexylglycocyamidine, 1-phenyl-3-n-octylglycocyamidine, 1-phenyl-3-decylglycocyamidine, 1-n-amyl-3-isopropylglycocyamidine, 1-n-octyl-3-n-butylglycocyamidine, 1-n-octyl - 3 - tetradecylglycocyamidine, 1-n-butyl-3-(1-naphthyl)-glycocyamidine, and 1 - (2 - ethylhexyl) - 3 - phenylglycocyamidine.

It has been discovered that a glycocyamidine of the above type may be readily prepared by reacting an alkali-forming metal salt of a mono-substituted cyanamide of the formula:

in which M is an alkali-forming metal, z is an integer not greater than 2 and R has the meaning shown above, with a haloacetamide of the formula

in which **X** is a halogen and **R'** has the meaning shown above, in the presence of a solvent.

The term "alkali-forming metal" as used in this specification and claims is intended to cover the alkali and alkaline earth metals.

A typical reaction in which sodium phenylcyanamide is reacted with *o*-bromo-N-n-octyl-

2

acetamide to produce 1-phenyl-3-n-octylglyco-cyamidine may be illustrated as follows:

15 Typical examples of solvents which may be employed in the presses are water, the low molecular weight aliphatic monohydric alcohols such as, for example, methyl, ethyl, isopropyl, n-propyl,
20 n-butyl, tert.-butyl and sec.-amyl alcohol; ketones such as acetone, methyl ethyl ketone, methyl n-propyl ketone, methyl isobutyl ketone, methyl benzyl ketone, cyclohexanone, and acetophenone; alkyl esters of aliphatic monocarboxylic acids
25 having boiling points less than 200° C. such as ethyl acetate, n-propyl acetate, n-butyl acetate, iso-butyl acetate, 2-ethylhexyl acetate, ethyl propionate, methyl butyrate and n-propyl valerate; aromatic nitriles and aliphatic saturated nitriles having boiling points not greater than 220° C. such as benzonitrile, acetonitrile, propionitrile, isobutyronitrile, and n-capronitrile.

The reaction is preferably carried out at a temperature within the range of from about 20° to 150° C. However, temperatures outside of this range may be employed depending upon the type of reactants and solvents utilized.

The invention is further illustrated by the following examples in which the parts are by weight.

Example 1

14 parts of sodium phenylcyanamide and 9.4 parts of chloroacetamide were dissolved in 100 parts of water and allowed to stand at room temperature (20°-25° C.) for 48 hours. The resulting precipitate was filtered, washed with water, and dried at 65° C. 9 parts of 1-phenylglycocyamine were obtained. The product was a colorless crystalline material melting at 235°-240° C.

Example 2

A mixture of 14 parts of sodium phenylcyanamide, 9.4 parts of chloroacetamide and 200 parts of acetone was heated to reflux for a period of 4 hours in a vessel equipped with a stirrer and reflux condenser. The mixture was cooled to room temperature and filtered. The filter cake was washed with water and then dried at 65°C., giving 9.1 parts of 1-phenylglycocyamidine.

in 50 parts of water and allowed to stand at room temperature for 48 hours. The resulting precipitate was filtered, washed with water and dried at 65° C. 7 parts (67% yield) of 1-p-chlorophenylglycocyamidine were obtained. After recrystallization from acetone, the product was a tan-colored, crystalline material melting at 275°-278° C. with decomposition.

The glycocyanimidines, prepared by the methods 10 of the present invention, are adapted for various uses, more particularly as chemotherapeutic agents, bactericides, and catalysts for the polymerization of unsaturated organic compounds to form high molecular weight linear polymers.

15 While the invention has been described with particular reference to specific embodiments, it is to be understood that it is not to be limited thereto but is to be construed broadly and restricted solely by the scope of the appended
20 claims.

卷之三

Example 2 was repeated using 200 parts of acetonitrile in place of the acetone as the solvent for the reactants. 10.6 parts of 1-phenylglycocyamine were obtained.

Example 4

Example 2 was repeated using 200 parts of ethyl acetate in place of the acetone. 12.5 parts (71% yield) of 1-phenylglycocyamidine were obtained.

Example 5

A mixture of 4.4 parts of sodium n-octyl-cyanamide, 2.4 parts of chloroacetamide and 100 parts of acetone was heated to reflux for three hours. The acetone was distilled off and the residue was washed with water to remove the by-product sodium chloride. 3.12 parts of 1-n-octylglycocyamidine were obtained. After recrystallization from alcohol, the product was a colorless crystalline material melting at 239°-244° C.

Example 6

A mixture of 14 parts of sodium phenylcyanamide, 25 parts of α -bromo-N-n-octylacetamide and 100 parts of ethyl alcohol was heated to reflux for two hours and then allowed to stand at room temperature for 16 hours. The reaction mixture was filtered to remove the precipitated sodium bromide. The filtrate was heated to distill off the ethyl alcohol. The residue was recrystallized twice from methyl alcohol, giving 8 parts of 1-phenyl-3-n-octylglycocyamidine, a colorless crystalline material melting at 86°-88° C. 45

Example 7

A mixture of 14 parts of sodium phenylcyanamide, 17 parts of α -chloroacetanilide and 300 parts of acetone was warmed on a steam bath for one hour, then allowed to stand at room temperature for 48 hours. The acetone was distilled off, and the residue was washed with water and dried at 65° C. 22 parts (87% yield) of 1,3-di-phenylglycocyanimidine were obtained. After recrystallization from acetone, the product was a colorless crystalline material melting at 164°-165° C.

Example 8

A mixture of 14 parts of sodium phenylcyanamide, 21.5 parts of α -chloro-p-nitroacetanilide and 150 parts of ethyl alcohol was heated to reflux for three hours and then allowed to stand at room temperature for 16 hours. The reaction mixture was filtered. The filter cake was washed with water and then dried, giving 23 parts (78% yield) of 1-phenyl-3-p-nitrophenylglycocyamide. After recrystallization from acetone, the product was a yellow, crystalline material melting at 271°-273° C.

Example 9

8.73 parts of sodium-p-chlorophenylcyanamide and 4.68 parts of chloroacetamide were dissolved

wherein R represents a member of the group consisting of alkyl and aryl radicals, and R' represents a member of the group consisting of hydrogen, alkyl and aryl radicals, which comprises reacting an alkali-forming metal salt of a mono-substituted cyanamide of the formula

in which M is an alkali-forming metal, z is an integer not greater than 2 and R is a member of the group consisting of alkyl and aryl radicals, with a haloacetamide of the formula

in which X is a halogen and R' is a member of the group consisting of hydrogen, alkyl and aryl radicals, in the presence of a solvent, and recovering the glycoxyamidine.

2. The method of claim 1 in which the reaction is carried out at a temperature within the range of from about 20°-150° C.

3. A method of preparing 1-phenylglycocyamide which comprises reacting sodium phenylcyanamide with chloroacetamide in the presence of a solvent, and recovering the 1-phenylglycocyamide.

4. A method of preparing 1-n-octylglycocyamine which comprises reacting sodium n-octylcyanamide with chloroacetamide in the presence of a solvent, and recovering the 1-n-octylglycocyamine.

5. A method of preparing 1-phenyl-3-n-octylglycocyamidine which comprises reacting sodium phenylcyanamide with α -bromo-N-n-octylacetamide in the presence of a solvent, and recovering the 1-phenyl-3-n-octylglycocyamidine.

Certificate of Correction

June 19, 1951

ERICK I. HOEGBERG

It is hereby certified that error appears in the printed specification of the above numbered patent requiring correction as follows:

Column 2, line 17, for "presses" read *processes*;
and that the said Letters Patent should be read as corrected above, so that the same may conform to the record of the case in the Patent Office.

Signed and sealed this 28th day of August, A. D. 1951.

[SEAL]

THOMAS F. MURPHY,
Assistant Commissioner of Patents.
